DOOR

Robert E. West, Dolington Road, Yardley, Pa.

Filed Jan. 11, 1963, Ser. No. 73,141

Term of patent 7 years

(Cl. D13—1)

Fig. 1.

Fig. 2

Fig. 3

FIG. 1 is a front elevation of the door embodying my new design;

FIG. 2 is a side view of the door embodying my new design; and

FIG. 3 is a top plan view of the door embodying my new design.

The rear of the door is plain.

The dominant features of my design reside in the portions shown in full lines.

I claim:

The ornamental design for a door, as shown and described.
